Primary Examiner — Marie D. Fast Horse*Assistant Examiner* — Altaira J Swangin(74) *Attorney, Agent, or Firm* — Ricky Lam(57) **CLAIM**

The ornamental design for a computer monitor, as shown and described.

DESCRIPTION

FIG. 1 is a front perspective view of a computer monitor, showing my new design;

FIG. 2 is a rear perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof;

FIG. 8 is a bottom view thereof; and,

FIG. 9 is an enlarged detail view of area 9 in FIG. 2.

The dash-dot broken lines represent the extents of the enlarged detail view and form no part to of the claimed design.

All remaining broken lines in the drawings illustrate portions of the computer monitor that form no part of the claimed design.

1 Claim, 9 Drawing Sheets(56)
